UNITED STATES PATENT OFFICE

STEWART ROY ILLINGWORTH, OF BRYNFEDWEN, RADYR, WALES, ASSIGNOR TO THE
ILLINGWORTH CARBONIZATION COMPANY, LIMITED, OF MANCHESTER, ENGLAND

APPARATUS FOR THE MANUFACTURE OF CARBONIZED FUEL

Application filed June 25, 1930, Serial No. 463,746, and in Great Britain April 18, 1929.

This invention relates to an apparatus for feeding or charging granular material, more especially coal into a storage bunker or other container.

5 The invention is more particularly intended for use in charging a brickwork retort having rows of carbonizing retorts, such as illustrated in my prior British Patent No. 245,190 and with reference to which it is 10 hereinafter described.

In the specification of my prior British Patent No. 248,077, we have described a process in which vibration is imparted to the retort during the period of charging and/or 15 during the process of carbonization before the coke structure has been formed, and by means of which a product of increased density and hardness can be obtained and coals of lower caking quality employed. In 20 this process the retort may be vibrated by tapping its upper part with blows in a vertical direction and in some cases pressure is applied to the fuel during vibration.

It has also been proposed in a continuously 25 operating gas or like retort in which the coal or other fuel is continuously distilled to provide constant stroke stamping or packing members adapted to contact with and thus to pack the head of coal in the mouth of the retort, the impact of the stamping members 30 causing a vibration to pass to the material in the distillation chamber which facilitates its downward movement to discharge and prevents stoppage by caking on the walls of 35 the chamber.

The present invention is however, more particularly intended for use with a process of carbonization where the carbonizing period is distinct from and takes place after 40 the operation of filling the carbonizing retort, the object of the invention being to tamp or pack the charge from the start of the feeding and as the level of the material in the retort rises.

45 We have found that by tamping the coal as it is fed into the retort, in some cases a greater density can be obtained than in our previous process while it is no longer necessary to vibrate the retort.

50 According to the present invention there-

fore, we tamp or pack the charge of coal or other granular material while it is being fed into the retort or other container in such manner that the finer sizes of coal fill the voids between the larger sized particles.

The coal or other material is tamped by means, such as a tamping rod which is given a reciprocating movement within the retort or container to impart a succession of taps or blows to the head of the charge, either 55 continuously or intermittently, during the operation of feeding, the arrangement being such that the stroke of the tamping rod structure as a whole automatically decreases with the rise of the head of coal within the retort 60 or container. While it is preferable to tamp continuously the retort may be charged in two or more stages, that is to say only half or less than half the complete charge to fill the retort, is fed at a time, each such charge 65 being submitted to a number of taps.

It will however, be found more satisfactory to tamp the charge continuously, starting tamping at a height of about 6" from the bottom of the retort. It is to be understood 75 also that the tamping of the charge is not intended to produce consolidation by means of a crushing effect, but rather solely by the vibration set up. For this reason the tamping rod should consist of a comparatively 80 light member reciprocating at high speed, and for a 4" stroke about 60 taps per minute has been found suitable. In a tapered carbonizing retort the retort having a mean cross sectional area of 16" x 6". 12' (high) 85 a tamping rod having a head of 2" diameter and combined weight of about 30 lbs. will be found to give good results; giving a 20% increase over loose filling. It will be clear that for a larger stroke, a tamping rod of 90 less weight may be employed, insomuch as the tamping rod does not have to withstand any mechanical resistance on striking the coal it is naturally a light member and its gross weight need not exceed 50 lbs.

95 The tamping rod may be actuated by means of a reciprocating bar, by means of which it is supported, being connected thereto by a clutch so arranged that resistance to downward movement of the rod releases the clutch,

allowing the rod to move upwardly with respect to the reciprocating bar, up which it climbs as the retort fills. In order to close the door of the charge hopper when the retort is full, a stop may be provided on the tamping rod adapted to engage a trip lever which releases a catch holding the feed door open.

Apparatus suitable for charging a series of rows of retorts comprises a charging car transversable over a track arranged to pass over each row of retorts, a hopper carried thereby, doors having feed trays and corresponding in number to the retorts in each row, and tamping rods corresponding therewith which are actuated by reciprocating bars operated from crank mechanism on the car.

Means may be provided for opening the doors together; each door is closed on release of its catch by the corresponding tamping rod when the rod has reached a height corresponding to the limit of its upward movement on the reciprocating bar when the retort is fully charged.

The following table gives a comparison of the density between loosely filled retorts and retorts filled with my tamping apparatus:

30.	Volatile of coal	Loose filling		Tamped	
		Weight	Density	Weight	Density
				Pounds	Pounds
31.8	Per cent	2375	.889	2650	.951
25.7		2480	.894	2830	.986
34.9		2170	.887	2420	.948
35		2450	.899	2716	.962

For general purposes it will be found sufficient to add about 10% by weight of fines (less than $\frac{1}{2}$ inch mesh) to the normal charge, or the charge may be ground to produce fines. By means of this invention it is however possible with certain non-caking and caking (bituminous) coals, to reduce the amount of caking coal required from say 45 50-30%, provided the caking coal be ground fine (to pass 60 mesh) and the charge tamped.

The resultant coke is of course dependent on the size of the coal.

The invention is illustrated in the accompanying drawings in which:—

Figure 1 is a diagrammatic elevation of a combined mechanism for charging and tamping a series of rows of retorts, such as the carbonizing or sub-retorts illustrated in the Illingworth British Patent No. 245,190. Figure 2 is a detail of a part thereof.

Figure 3 is a detail section of an alternate form of clutch mechanism, Figure 4 illustrating the clutch release with a similar form of clutch.

In the drawings, A indicates generally a charging car having wheels B by means of which it is traversable over a track C passing over a series of rows of carbonizing or sub-

retorts, the top-part of one of which retorts is seen at D.

The car may be hand or power driven. E is a charging hopper for charging a row of sub-retorts simultaneously but which if necessary (according to the number of retorts in the row) may be subdivided into separate compartments, this sub-division not being shown.

Referring to Figures 1 and 2, the hopper E is provided with outlets or discharge pipes 1, corresponding in number to the number of carbonizing retorts in each row or to be charged simultaneously, corresponding doors 2 and feed trays or chutes 3. The chutes 3 deliver the material into mouth pieces 4, the throats of which extend downwardly a sufficient distance to discharge directly into each carbonizing retort.

Means (not shown) is provided for opening all the doors simultaneously, and each door is then held open by means of a latch 5 connected by a link 6 to a trip lever 7. It will thus be seen that when the trip lever is operated, the corresponding latch 5 will be moved to release the door held thereby which will then gravitate to the closed position.

Mounted on the car A is a rocking beam 8, operated through mechanism indicated generally at 9 and which beam is connected to a vertically reciprocating operating bar 10 whose other, lower end is connected to an arm 11 pivotally supported by the hopper E. 12 is a tamping rod which is connected by means of a clutch mechanism (see particularly Figure 2) to the operating bar 10.

This clutch mechanism consists of a carrier member 13, in which the tamping rod 12 is secured, slidable on the reciprocating bar and carrying an eccentrically mounted flat ended finger 14 whose end is adapted normally under the weight of the outer end of the finger frictionally to engage a surface on the reciprocating bar, the arrangement being such that any upward movement of the bar with respect to the tamping rod tends to move the finger into gripping engagement, whereas downward movements of the bar 10 free it therefrom. It is clear that the clutch will operate in the manner of a pawl and ratchet.

The outer end 15 of the finger 14 functions as a dog to engage the depending cam-like end of trip lever 7 and thus release the latch 5. When therefore a retort is full, the tamping rod 12, which climbs up the bar 10 as the retort fills, will owing to cam-like engagement of the stop 15 with the lever 7 cut off the supply of material to the retort by releasing the latch 5.

Hand operated lifting and lowering gear is also preferably provided for lowering the tamping rods into the retorts and for giving them a final lift clear of the mouths of the retorts when it is desired to move the car to

charge another retort. For this purpose a bar 16 operated by pulley mechanism 17 may be arranged on the car so as to engage under the clutch members slidable on the 5 reciprocating bars and which support the tamping rods, simultaneously engaging the outer ends 15 of the fingers and thereby releasing the clutches so that the tamping rods can be raised independently.

10 Referring now to Figure 3, the tamping rod 12 is telescopically mounted within a tube 18, which is telescopic within a tube 19, these two tubes, 18 and 19, constituting a telescopic equivalent of the operating- 15 rod 10.

Fast on the lower ends of each tube 18 and 19 is a housing member 20 formed with a conical opening 21 within which rides a cage 22. The cage 22 carries ball bearings 23 20 adapted respectively to contact with the tube 18 and tamping rod 12. Each cage also is provided with a collar 24 and as shown in Figure 3 is spring urged by spring 25, or by means of the weight 26 (Figure 4) to a 25 position where the balls 23 will wedge themselves into the conical annulus formed between the conical wall of the cage 22 and the respective outer surfaces of the tube 18 and rod 12. It is thus obvious that the rod 30 12 is free to telescope within or move upwardly inside the tube 18 but that it is prevented by the locking action of the balls 23 in the cage 22 against any outward or downward movement. These two telescopic rods 35 18 and 19 are, as stated, used in lieu of the single operating-rod 10 and the purpose is to shorten the length of the operating rod to the end that space above the retort may be saved. When the tamping rod 12 is to be 40 raised out of the retort, either one or both clutches have to be released by such means as shown in Fig. 1, namely a bar 16, or by a forked hand lever 27, shown in Fig. 4, or by any other suitable means. The releasing 45 means may engage under the collars 24 so as to raise the ball carrying tubes 22 upwardly into released position. In Fig. 4 I show a weight 26 in lieu of the collar 24 to thus do away with the springs 25.

50 Normally when feeding coal or other granular material into a hopper it will be observed that the coal tends to build itself up in a conically or similar shaped heap beneath the mouth of the discharge with the 55 result that the heavier pieces of coal run down the sides of the heap thus formed causing an uneven distribution with the fines in the centre.

By means of this invention it is possible 60 to control the surface of the charge as it is fed into the hopper or retort so that it is maintained substantially level throughout charging and the heavy and light particles 65 evenly distributed over the cross section of the hopper. This feature it will be appre-

ciated is an important factor in retort practice where it is essential that carbonization is uniform over the whole retort.

It will be noted that in the apparatus of this invention the coal is fed into the centre 70 of the retort and that the axis of the tamping rod is located centrally within the retort so that the axis of the feed and tamping coincide with one another.

It should be understood that while the present invention is more especially intended for use in charging retorts of carbonizing apparatus, it is also applicable to charging apparatus generally.

What I claim is:—

1. In tamping mechanism suitable for charging granular material into a substantially vertical carbonizing retort, the combination of means for continuously feeding the material into the retort, a tamping member adapted to be reciprocated within said retort for imparting a succession of taps to the head of material during charging, driving means for continuously reciprocating said member at high speed, and clutch means for automatically clamping said member to the driving means during upward movement, embodying devices whereby said clutch means is released on resistance to each downward movement of said tamping member. 95

2. In tamping mechanism suitable for charging granular material into a substantially vertical carbonizing retort, the combination of means for continuously feeding the material into the retort, a tamping structure 100 embodying a tamping member adapted to be reciprocated within said retort for imparting taps in rapid succession to the head of material during charging, driving means for continuously reciprocating said tamping structure at high speed, and means for automatically decreasing the operative length of said tamping structure with the rise of material in the retort. 105

3. In tamping mechanism suitable for 110 charging granular material into a substantially vertical carbonizing retort, the combination of a tamping member adapted to be reciprocated within said retort for imparting a succession of taps to the head of material during charging, driving means for reciprocating said member at high speed, and clutch means for clamping said member to the driving means during upward movement, but which is released on resistance to downward movement of said tamping member, 115 said driving means embodying a pair of telescoping tubes, a clutch cooperating between the two tubes, and another clutch cooperating between the inner tube and said tamping member. 120

4. In a tamping mechanism, a tamping-rod whose tamping end is adapted to enter a container for the tamped material, an actuating-rod arranged in parallelism with the 125 member. 130

upper portion of said tamping-rod, means for reciprocating said actuating-rod, clutch devices associated with said tamping-rod and actuating-rod whereby on the up movement of said actuating-rod the tamping-rod will be lifted, and on the down movement of said actuating-rod the tamping-rod will be released as soon as it meets with resistance at its lower end and permitted to slide upwardly on said actuating-rod, a hopper having a delivery spout for delivering the material into said container, a closure-device for this spout, closure-actuating means, and a device associated with the tamping-rod whereby when said tamping-rod reaches a predetermined height said closure-actuating means is operated to close the closure-device and thus stop the discharge of material into the container.

20 In testimony that I claim the foregoing as my invention I have signed my name this twelfth day of June, 1930.

STEWART ROY ILLINGWORTH.
